UNITED STATES PATENT OFFICE.

JAMES P. HILLARD, OF FALL RIVER, ASSIGNOR OF ONE-HALF TO GEORGE DRAPER & SONS, OF HOPE DALE, MASSACHUSETTS.

TOOL FOR WEAVER'S USE.

SPECIFICATION forming part of Letters Patent No. 390,599, dated October 2, 1888.

Application filed December 21, 1887. Serial No. 258,575. (No model.)

To all whom it may concern:

Be it known that I, JOHN P. HILLARD, of Fall River, county of Bristol, State of Massachusetts, have invented an Improvement in 5 Tool for Weavers' Use, of which the following description, in connection with the accompanying drawing, is a specification, like letters on the drawing representing like parts.

In the manufacture of cloth on looms it frequently happens that a thread is broken or gets out of place in either the weft or warp, and so, also, it is necessary at times to pick out a thread or remove a bad place or knot.

To enable these faults to be corrected, the 15 weaver is provided with a sort of comb, consisting of needle-like teeth, held side by side in a back composed of a piece of sheet-brass bent into **U** form, and with a pair of scissors.

The comb referred to is used by the weaver 20 to scratch the surface of the cloth where a thread is omitted, or where the threads are improperly spaced so as to leave a thin place, the operator by such scratching moving the threads to place them at substantially equal 25 distances apart.

The use of the comb referred to with its detached needle like teeth held separably in a back is very objectionable, for the reason that, as the comb wears, the strain upon the teeth 30 loosens them and they become detached, one here and one there, and enter the cloth, where they remain--being overlooked by the operator--while the cloth is subjected to subsequent dyeing or finishing operations.

35 A needle-point so left in the cloth, especially when passing through the dyeing or drying operations, invariably causes a slit or tear in the cloth, greatly damaging the same and destroying its value in the market.

40 This breaking out of the cloth by the pres-

ence in it of a comb-tooth is a very serious evil, and results yearly in a very considerable loss. To overcome this trouble I have devised a comb the teeth of which cannot be detached one from the other, and at the same time--to do 45 away with other instruments--I have provided the comb with a picking-out point.

The drawing represents a tool embodying my invention.

In the manufacture of my improved tool I 50 take, preferably, a piece of sheet-steel about two and a half inches long and about one and a quarter inch wide, more or less, and provide the same at one edge, by cutting or filing, with a series of teeth, as *a*, by which to scratch the 55 face of the cloth where necessary, the said teeth being integral with the body of the tool.

At one end the body *d* of the tool has a picking-out point or prong, *b*, and at its other end a pair of pinchers, *c*, composed of two like 60 jaws, to be manipulated as tweezers, the pinchers enabling the operator to pull or cut off any knot or bunch.

My improved tool may be made cheaply, and by its use all liability of leaving teeth in 65 the cloth to its injury, and to the injury of the machinery through which the cloth is passing, is completely obviated.

I claim—

The body *d* of the tool toothed along one 70 edge, as at *a*, and provided at or near one end with the point *b*, substantially as described.

In testimony whereof I have signed my name to this specification in the presence of two subscribing witnesses.

JAMES P. HILLARD.
